BENJAMIN BATES, OF BALTIMORE, MARYLAND.

Letters Patent No. 101,415, dated April 5, 1870.

IMPROVEMENT IN APPARATUS FOR GENERATING CARBONIC ACID.

The Schedule referred to in these Letters Patent and making part of the same.

To all whom it may concern:

Be it known that I, BENJAMIN BATES, of Baltimore, in the county of Baltimore and in the State of Maryland, have invented certain new and useful Improvements in Safety-chambers for Gas-Generators; and do hereby declare that the following is a full, clear, and exact description thereof, reference being had to the accompanying drawings and to the letters of reference marked thereon making a part of this specification.

The nature of my invention consists in the attachment of a tumbler or hollow cap to carbonic-acid gas or other generators, for the purpose of preventing the compound from passing over into the washer by the force of gas.

In order to enable others skilled in the art to which my invention appertains to make and use the same, I will now proceed to describe its construction and operation, referring to the annexed drawings which represent a side view of a generator, part in section, with my tumbler or cap attached thereto.

In all generators for manufacturing carbonic-acid gas, soda, marble-dust, and whiting are used in combination with oil of vitriol. This compound becomes thick, and is thrown against the sides of the generator, filling up (without great care) the space for the gas to pass over into the washer, therefore, when the gas is let onto the beer or soda-fountains from the washer, the gas in the generator must force the compound into the mouth of the pipe over into the cooler or washer, thereby filling it up at the bottom and causing the water to rise in the washer till it reaches the gas-cock, when, on letting on the beer or soda-

fountains, what should be pure gas, water is taken in impregnated with marble and acid, destroying the beer or soda and making it unfit for use.

To obviate this difficulty is the object of my invention.

In the annexed drawings—

A represents the usual gas-generator, having an agitator revolving within it.

On the side of the generator is an opening having a flange or collar, a, projecting on the outside around the same.

On this collar is screwed a tumbler or hollow cap, B, forming a chamber, C.

The pipe for conducting the gas from the generator to the cooler or washer is screwed on at the top of this cap or tumbler. This prevents the compound from clogging up said pipe.

The tumbler B can readily be taken off to clear the generator of incrustation or any thing that may prevent the generator from working in a proper manner.

Having thus fully described my invention, What I claim as new, and desire to secure by Letters Patent, is—

In combination with a carbonic-acid gas or other generator, a tumbler or hollow cap attached to the generator in any suitable manner, substantially for the purposes herein set forth.

In testimony that I claim the foregoing I have hereunto set my hand this 10th day of February, 1870.

BENJAMIN BATES.
